Primary Examiner — Mary Ann Calabrese*Assistant Examiner* — Sloan Rozin(74) *Attorney, Agent, or Firm* — McDonald Hopkins LLC(57) **CLAIM**

The ornamental design for a printer sheet with wristband, as shown and described.

DESCRIPTION

FIG. 1 is a front perspective view of the design;

FIG. 2 is a front view of the design;

FIG. 3 is a rear view of the design;

FIG. 4 is a first side view of the design;

FIG. 5 is a second side view of the design;

FIG. 6 is a top view of the design; and,

FIG. 7 is a bottom view of the design.

The broken line showing of elements on the printer sheet with wristband is for the purpose of illustrating portions of the article and form no part of the claimed design.

1 Claim, 3 Drawing Sheets(56)
